UNITED STATES PATENT OFFICE

FRANK E. JONES, OF PAWTUCKET, RHODE ISLAND, ASSIGNOR TO HEMPHILL COMPANY, OF CENTRAL FALLS, RHODE ISLAND, A CORPORATION OF MASSACHUSETTS

KNITTING MACHINE AND PROCESS FOR PRODUCING SPLIT FABRIC

Application filed June 12, 1923. Serial No. 644,874.

This invention relates to knitting machines and processes for producing split fabric, and more especially to circular, automatic, knitting machines intended to knit split foot hosiery and to processes for producing split foot hosiery.

This invention is so far as common features are concerned an improvement upon the construction shown in the patent to Robert H. 10 Lawson, No. 1,458,833, June 12, 1923.

In order that the principle of the invention may be readily understood, I have disclosed in the accompanying drawings mechanism constituting an embodiment of my invention 15 and by which mechanism the process of my invention may be practiced.

In said drawings,

Fig. 1 is a front elevation of the entire machine;

20 Figs. 1a and 1b are side elevations of two forms of pattern chains for making two forms of zigzag suture seams;

Fig. 2 is a rear elevation of the entire machine;

25 Fig. 3 is an end elevation thereof;

Fig. 4 is a view of the machine partly in plan and partly in section upon the line 4—4 of Fig. 1;

30 Fig. 5 is a front elevation of the mechanism shown in Fig. 4;

Fig. 6 is a rear elevation of the mechanism shown in Fig. 4;

35 Fig. 7 is a section upon the line 7—7 of Fig. 4 and looking toward the right in said figure;

Fig. 8 is a left end elevation of the mechanism shown in Fig. 4, looking toward the right in said figure;

40 Fig. 9 is a side elevation of a so-called seamless, split work stocking made in accordance with my invention;

45 Fig. 10 is an enlarged view showing the character and relative location of certain of the loops of the suture seam formed in accordance with my invention and according to one arrangement of the pattern control;

50 Fig. 11 is a development of the cams and some of the needles and jacks preferably employed in the practice of my invention;

Fig. 12 is a side elevation showing one of the needles and its jacks;

Fig. 13 is a development showing the arrangement of cams, needles and jacks when knitting at the regular cam set the relatively 55 narrow stripe with which the split work may be commenced;

Fig. 14 is a similar development but indicating the knitting of a tapered continuation of said stripe;

Fig. 15 is a diagram indicating the formation of the stripe and a part of the zigzag continuation thereof;

Fig. 16 is a horizontal section taken through the needle cylinder and showing the 60 long and short needle butts in a somewhat diagrammatic manner;

Fig. 17 is a similar view but showing the 65 jack butts, and the jack widening picker in plan; and

Fig. 18 is a front elevation of a modified 70 form of my invention.

My invention, while applicable to the production of numerous fabrics as well as to various parts of hosiery, more particularly 75 relates to means for producing reinforced or contrasting areas in hosiery, such, for example, as high splices of triangular or other suitable shape by means of split work, and to a method or process by which such reinforced or contrasting areas are produced. I shall herein disclose mechanism whereby this 80 result is accomplished. Such mechanism may be used with many different types of knitting machines. I will, however, without 85 limiting myself thereto, disclose the same as used in connection with a circular knitting machine of the so-called Banner type and organized for producing split work, but not in itself capable of effecting the production of 90 a reinforced or contrasting area having non-parallel sides, to which latter feature my invention is more particularly directed.

I will first describe in necessary detail a circular knitting machine for producing a 95 stocking of split work and will then disclose the fundamental changes therein and with which my invention is particularly concerned.

The knitting machine herein disclosed, but 100

to which my invention is in no wise limited, embodies the characteristics of the so-called Banner machine fully disclosed in the U. S. patent to Hemphill, No. 933,443, dated September 7, 1909. Said machine has a frame 1 within which is mounted a needle cylinder 2 preferably, although not necessarily revoluble, and a non-revoluble cam carrier having an annular portion or ledge 4. Mounted 5 in the frame 1 is a main shaft 5 carrying suitable pulleys 6, 7, 8, respectively employed as quick speed, slow speed and loose pulleys. A pattern shaft 9 is mounted in said frame and has thereon an appropriate cam or pattern drum 10. Upon said pattern drum is a 10 peripheral rib or cam 11 which engages with a follower 13 carried by a pivoted clutch shifting lever 14 connected with the usual clutch for shifting from reciprocating to 15 rotary driving instrumentalities, and vice versa, said latter instrumentalities being well known features of said Hemphill patent, and for further information concerning the same reference may be had thereto. The follower 20 13 is adapted to travel through cross slots 12 from one side of the rib 11 to the other so as to effect the shifting of said clutch member. One of said cross slots is shown in Fig. 1.

30 By means of the mechanism just described the needle cylinder 2 is adapted to be given at certain times in the knitting operation a continuous rotary movement, as, for example, during the knitting of the leg of the stocking, 35 while at other times said cylinder is given a to and fro or reciprocating movement not only during the knitting of the heel and toe pockets of the stocking, but also during the knitting of a portion of the ankle, and particularly that part which includes the high 40 splice and also during the knitting of the foot, although, as stated, the disclosed embodiment of my invention pertains more particularly to the knitting of the high splice by a reciprocating movement, whereby through 45 the formation of suture seams at opposite sides of the stocking a reinforcing or contrasting area is presented, said suture seams being desirably, and as herein disclosed, 50 along lines which as as entirely are non-parallel to the wales of the fabric; and as herein shown are along lines crossing a series of consecutive wales of the fabric. As 55 hereinafter more fully disclosed said suture lines are or may be at one end in proximity to each other and they slope in opposite directions at desirably substantially equal angles, whereby in the particular embodiment herein disclosed a generally triangular 60 area is bounded on two sides thereby. In accordance with my invention, the reinforced or contrasting area may be at the back or the front of the stocking, and may be of triangular or other suitable shape involving the 65 production of non-parallel suture lines, as

hereinafter more fully set forth, and the fabric, if a stocking, may be commenced at either end, as, for example, the top of the leg or the top of the toe.

Depending upon whether the stocking is 70 commenced at the top of the leg or at the toe of the stocking, said suture lines either commence or terminate in proximity to each other in the illustrated embodiment. I will more particularly describe that embodiment 75 of the invention wherein the knitting is begun at the top the leg, in which case said suture lines (in the event that the reinforcing or contrasting area is not quadrangular in shape) commence in suitable proximity 80 to each other and diverge desirably in irregular lines and desirably at equal angles or symmetrically (though not necessarily symmetrically), whereby a reinforced or contrasting area is produced, which is bounded 85 on two sides by said two suture lines. In the disclosed embodiment of the invention, said suture lines are inclined in a zigzag direction, thus crossing a series of wales.

The means whereby such suture lines are 90 produced will be hereinafter more fully set forth.

The cam plate 3 has provisions for a limited vertical movement, the same being herein mounted upon the usual cam slide 15 itself 95 mounted for vertical movement in the said frame 1 and carrying at its lower portion cam followers 16, 17, 18, adapted to engage ribs upon the cam 19 mounted upon and adapted to turn with the pattern shaft 9, 100 said cam being adapted to move said cam slide up or down to vary the length of the loops during the knitting of the leg and other portions of the stocking. My invention may be practiced upon either a spring beard needle 105 or a latch needle machine, but desirably upon a spring beard needle machine. For convenience of description, I shall refer to certain features more particularly pertaining to spring beard needle work, such, for example, 110 as the segmental or partial ring carrying the yarn guides. It is to be understood that I may employ latch needles, in which event a suitable latch ring will be substituted for the partial ring. Herein a partial ring 20 is pivoted at one side of the machine upon an upright post 21 by a pivotal pin 22. The said partial ring is normally locked in its operative position by a latch 23 engaging a pin 24 upon the partial ring.

The needles shown in the present embodiment of the invention are of the spring beard needle type, but as hereinbefore stated latch needles may be used within the scope of the invention. The needles of whichever type 125 employed are arranged in a circular series, but are in number consistent with the diameter of the work to be performed upon the machine. Desirably as many as two hundred and forty or two hundred and sixty needles 130

are provided in a three and a half inch diameter needle cylinder. These needles are divided into two substantially equal sets, one set here having long knitting butts and the other having the usual short knitting butts, said long butt needles, also termed "instep needles", being adapted to be withdrawn preferably by elevating them at suitable times in the operation of the machine by the usual instep cams 27, 28, as shown in Fig. 1. The said cams 27, 28 are mounted on slide 29 arranged to slide vertically in a standard 30 secured to the cam plate 3. Appropriate movement is imparted to said slide by a bell 15 crank lever 31 pivoted at 32 to the framing, one arm of said lever being connected by a link 33 with said slide 29, the other arm being connected at 34 with a link 35 connected in usual manner (not shown) with the upper 20 end of the clutch shifting lever 14. Said connections are such that when said clutch shifting lever 14 is in the position for rotary knitting, the cams 27, 28 will be in their lowermost or depressed positions, and when said lever 14 25 is in a position to effect to and fro or reciprocating knitting, said cams 27, 28 will automatically be moved to the upper position, and thereby effect the withdrawal of the instep or long butt needles whose butts are arranged 30 to engage said cam 27 and be elevated thereby, said cam 27 being far enough from the face of the needle cylinder to engage only the long butts, thereby permitting the short butts to pass without interference. The cam 35 28, however, is placed close up to the cylinder, so as to engage either long or short butts which happen to be in their elevated positions when said cam 28 and the cam 27 are depressed. Mounted upon the cam plate 40 3 with the instep cams is a cam block 37 arranged to slide radially with respect to the needle cylinder between suitable angle plates at opposite sides of said block and secured to the cam plate 3. A spring 38 is interposed 45 between said cam block and a suitable fixed abutment, such as the head of a screw 39, and constitutes means yieldingly to maintain said cam block in its operative position with respect to the needle cylinder. Said cam 50 block 37 herein constitutes the support for what are termed the primary knitting cams of the machine and herein consisting of the usual stitch cams 40, 41, a lower central guide cam 42 and an upper central guide cam or 55 member 43. The inner faces of the cams 40, 41, 42, 43 are concaved and lie normally in the plane coinciding with the outer face of the needle cylinder 2, said cams being withdrawn from this position only when it 60 is desired to level the needles for transferring or when it is desired to withdraw said cams to get at the needles of the cylinder for the purpose of withdrawing or replacing needles. The usual means employed in the Banner ma- 65 chine for either manually or automatically

retracting the cam block 37 for the purpose just described may be and herein are employed, but need not be fully described. They may be such as are shown in the said Lawson patent. The withdrawal of the cam block 70 37 may serve to rock the latch to disengage the partial ring 20, thereby permitting said ring to be moved upward by a suitable spring provided for that purpose. Any other suitable construction to this end may, however, 75 be provided.

The said cam block 37 is also provided with a pair of narrowing picks 40', 40' pivoted upon said block in a manner characteristic of said Banner machine and arranged to operate in the usual manner.

The said partial ring 20 is also provided with the usual supply of yarn levers at the primary side, as indicated generally at 41' in Fig. 1. These levers may be and are herein indicated as five in number and are herein-after referred to as the primary yarn guides. The said levers are desirably operated in the usual manner from the pattern drum 10. Also supported upon said ring 20 is an arm 42' for the usual yarn clamping and yarn cutting devices for the primary yarns. These may be of the usual type and are operatively connected with the pattern shaft to operate automatically with the changing of the yarn. 90 The needle cylinder is provided with the usual web holder bed surmounted by the web holder cam ring 43', shown in Fig. 1, of the usual Banner construction and having spaced lugs to engage the partial ring 20 so as to effect 95 relative movement between said cam ring and the sinker bed ring. Said parts operate in the usual manner and require no further description.

The parts hereinbefore described are generally common to the Banner type of knitting machine and are operated automatically from the pattern shaft 9 by pattern mechanism indicated generally in Fig. 1.

Inasmuch as an important and indeed the main object of the invention is to provide a machine for knitting split fabric with suture lines which are inclined as an entire either converging or diverging, but are zigzagged with both inclined and parallel portions, a 110 secondary set of knitting cams is provided, which set is indicated generally at 44 in Fig. 11. This set of knitting cams preferably includes a pair of stitch cams 45, 46, a lower guide cam 47 and an upper guide cam 48, said 115 upper guide cam being automatically radially moved at suitable times as hereinafter disclosed for permitting reciprocation of the needles. There is also provided an upper guard cam 49 for the upper guide cam, said 120 guard cam 49 being stationary.

The inner faces of said several cams are concaved and are arranged normally to lie in a plane substantially coinciding with the plane of the outer face of the needle cylinder,

which plane also coincides with the plane of the inner faces of the cams of said primary set. Appropriate supporting instrumentalities are provided for said secondary knitting cams to maintain such cams in substantially the same horizontal plane as are the primary knitting cams, whereupon certain needles including those with long knitting butts will be actuated during knitting of certain parts of the stocking or at substantially the same time that other needles including the regular short butt needles are acted upon as herein-after stated. Said secondary cams may be adjustable vertically with respect to the primary cams, in order to provide perfect alignment between the two, and for this purpose any suitable means may be provided. I have here indicated for the purpose the said cams as mounted upon a plate 50 which is attached to a slide 51 secured to the frame 1.

I preferably move the secondary knitting cams radially of the needle cylinder to withdraw them to positions where they will not act upon needle butts, as, for example, when the needles are to be levelled for transferring or when the needles may have become caught or are to be replaced by hand. For this purpose, any suitable means may be provided. The cam block for the secondary knitting cams is desirably capable of manual as well as automatic retraction, and for this purpose any suitable means may be provided. As more fully disclosed in said Lawson Patent No. 1,458,838, there are occasions during the operation of the machine when it is desirable to retract the upper guide cam 48 from its operative position independent of the cams 45, 46, as, for example, when strokes of reciprocation are to be made in the knitting of split work. For this purpose, said cam 48 may be slidably mounted in its cam block, so as to be withdrawn either manually or automatically, but preferably automatically and by means hereinafter disclosed, and not from the quadrant of the machine, as shown in said Lawson patent. The construction and operation of parts are such that desirably toward the end of each stroke of reciprocation the guide cam 48 is moved out and then returned, so as to permit the butts of the elevated needles that passed over the main knitting cams to pass by said cam 48 without being depressed into knitting position as would be the case if said cam 48 remained in action.

Means are provided for withdrawing the cams 44 during heel and toe work, but such movement does not interfere with the described withdrawal of the cam 48 during split work.

When an auxiliary or secondary set of cams is employed for split work, means must also be provided to feed yarn to the needles that are actuated by said auxiliary or secondary set of cams. Hence the secondary yarn guide

52 is provided upon the ring 20 in a position appropriate to said secondary knitting cam set, and herein substantially diametrically opposite to the primary knitting cams. The said secondary yarn guide 52 is in the form 70 of a lever pivoted at 53 to the ring 20, and the free end of said yarn guide is arranged in a suitable slot in the ring 20.

The purpose of the secondary cams, as previously stated, is to function certain of the needles during the knitting of split fabrics, and where the formation of such fabrics is limited to a certain portion of the knitted article, as, for example, the ankle portion and the foot of a stocking, the secondary yarn 75 guide must be moved into and out of its operative position when said secondary knitting cams are moved into and out of their operative positions.

The purpose of secondary cams 44 is, as previously stated, to function certain of the needles during the knitting of split work and where the formation of such fabric is limited to a certain portion of the knitted articles, as, for example, the ankle portion and the foot 80 of the stocking, the secondary yarn guide 52 must be moved into and out of its operative position when said secondary knitting cams are moved into and out of their operative positions. While this result may be effected in any suitable manner, I have herein represented the secondary yarn guide 52 as adapted to be elevated out of position by a lever 54 pivoted at 55 upon the framing and connected by rod 56 to the secondary cam block or the movable cam 48 in any suitable manner, so that the secondary yarn guide 52 is in operative position when the secondary cams are operative, and vice versa, is out of operative position when the secondary cams are inoperative.

The guard cam 49 may be shaped substantially as shown in the said Robert H. Lawson patent, and may be supported in the same manner.

The usual needle widening pickers 57, 58 for acting upon certain needles are pivotally mounted, and preferably means of any suitable type are provided for holding said pickers in their inoperative position when narrowing and widening operations are not to be performed.

Arranged at the back of the needle cylinder between the primary and secondary sets of cams is a switch cam 59 shown most clearly in Fig. 11, and which may be of usual construction, being arranged to engage only the long knitting butts and then only when the needle cylinder is travelling in a reverse direction. This causes the movement of the long knitting butt needles to the upper level.

When the butts of the needles are passing in the opposite direction, namely, forwardly along the usual channel for circular knit-

ting; the long butt needles will engage said switch cam 59 and throw the same up without changing the position of said needles, it being provided with a suitable shaft or pivot and with a spring for holding said cam in the position shown in Fig. 11.

In machines for producing split work prior to those of the said Robert H. Lawson patent, the needles have been arranged into 10 two groups equal or substantially equal in number, so that the suture lines or seams were substantially parallel. In said Lawson patent is disclosed the provision of two groups of needles adapted respectively to 15 work upon opposite parts of a stocking or other fabric in split work, certain needles being transferred from one of said groups to the other persistently as the work progresses, so that the number of needles in 20 one group is markedly increased and the number of needles in the other group is correspondingly decreased.

This latter principle of operation is followed in the present invention, but instead 25 of transferring a needle from one group to the other at each end of each partial course throughout the tapered formation or area, I transfer the needle from one group to the other at each end of a course or desirably a 30 series of courses, and then during one and preferably throughout a number of courses retain unvaried the number of needles in the two groups.

I then repeat the cycle of operations as 35 many times as desired, thus effecting the formation of what may be termed zigzag suture seams.

While this result, which so far as I am aware, is broadly new, may be effected in any 40 suitable manner, I desirably provide a single double-acting widening jack picker to act upon each of a series of jacks positioned below the needles or the jacks thereof, so as at the courses indicated to move the indicated jacks from an upper to a lower level, thereby causing said needles to function 45 with the smaller group.

I therefore provide means of any suitable type for retaining out of action at times the 50 said single acting widening jack picker, such means being controlled in any suitable manner. As hereinafter more fully disclosed, I also provide means whereby said widening jack picker is temporarily rendered inoperative 55 during a part of each stroke of reciprocation, so that said picker will not operate upon the outermost of the series of jacks, as more fully set forth.

As disclosed in said Lawson patent, jacks 60 were provided beneath substantially all of the short butt needles and so-called dummy jacks were provided beneath the long butt needles. In the disclosed embodiment of the invention, I provide jacks beneath the short 65 butt needles only, or rather beneath all the

short butt needles excepting such central needles as may be provided for knitting a relatively narrow stripe of any suitable length desirably along the median back line of the stocking. Such jacks are indicated at 70 60 in the several figures. As shown most clearly in Figs. 13 and 14, said jacks are of considerable length and are provided with butts 61. The said jacks are received in the needle grooves below the needles or below 75 the attached jacks of the needles if the latter construction be provided.

Herein I have represented in Fig. 12 a spring beard needle 62 having a beard 63 adapted to be closed by the presser 64. At 80 its lower end the said needle is desirably bent as indicated at 65 to engage the jack 66, which is in effect a permanent part of the needle when the needle and jack are in position in the machine. The jacks 60 are in each case 85 distinct from but adapted to move independent of its needle and also subsequently with its needle to move the latter. The said jacks 60 are in turn brought under the influence of the single double acting widening jack picker 112 hereinafter more fully referred to, and are thereby moved downwardly as indicated in the diagram Fig. 14, being brought under the influence of one or the other of two jack cams 86, 87 hereinafter more fully referred 90 to and shown clearly in Figs. 3, 4, 5, 8 and 11, and thereby moved to the lower level. The needles corresponding to the said jacks pass through and knit at the auxiliary cam set 44, but being short butt needles are not re-elevated by the instep cam 27 to the upper level and therefore thereafter knit at the regular 95 or primary cam set instead of at the auxiliary cam set.

The number of needles in the two groups 100 may differ with the same diameter of needle cylinder and same gauge of needle, in accordance with the different designs to be produced. In the event that the article being knitted is a stocking, and if the reinforced or contrasting area of the split work is a high splice of triangular form in approximation, the needles in the group which knits said high splice will at the commencement of the high splice be limited to a comparatively few in 105 number. In the present embodiment of the invention, I provide for the formation of a stripe at the back median line of the stocking. Such stripe may be of any suitable length but it is desirably relatively short as 110 indicated at 67 in Fig. 9, as the production of a long stripe will substantially increase the time required to knit the stocking. In the disclosed embodiment of the invention the said stripe 67 is desirably knitted by thirty- 115 six needles in a machine employing 248 needles in a three and a half inch diameter cylinder. Therefore the said thirty-six needles are not provided with jacks and this fact is indicated by the space 68 in Figs. 11 and 13, 120 125 130

The machine is operated to produce rotary seamless work down to the commencement of the stripe 67, and the machine then going into reciprocating knitting by division of the needles into two groups as disclosed in the said 5 Robert H. Lawson patent, a portion of the stocking is knitted corresponding to the length of the stripe 67 and as indicated by the parts within the bracket 67a in the diagram Fig. 15.

During the knitting of the said stripe 67 the widening picker 112 is out of operation, but being then brought into operation for desirably a plurality of courses, such, for example, as four, as indicated by the parts within 15 the bracket 68a of the diagram, Fig. 15, the stripe is widened at each side, or in other words, the high splice is commenced, being indicated by the line 68 in Fig. 9.

Thus I provide for the knitting of a 20 tapered high splice or other contrasting area but instead of continuously upon each partial course transferring a needle from each end of the larger group to the smaller group, I 25 do this only at intervals, thereby producing the oblique suture lines such as 68, 69, 70, 71, 72, 73, 74, etc. of Fig. 9, each of which crosses wales of the fabric, while between the adjacent oblique lines of suture stitches, 30 I form lines of suture stitches 75, 76, 77, 78, 79, 80 and 81, all of which extend along wales of the fabric without crossing the same. In the diagram, Fig. 15, the courses within the bracket 75a are knitted upon the same number 35 of needles, and the courses within the bracket 69a are each knitted upon an increasing number of needles. This operation is continued to the extent desired, and as here indicated down to the commencement of the heel 40 pocket 82.

The foot of the stocking may be formed by 45 split work as indicated by the line 83, and the number of needles in the two groups for the formation of the foot may be unvaried or may be varied as indicated for the formation of the high splice or otherwise.

If the contrasting or reinforcing area is to be at some other part of the stocking than the high splice area, obviously the grouping 50 of the needles will be different from that described, and the number of needles in each case will depend upon the size and shape of the reinforcing or contrasting area.

The stocking may be commenced either at 55 the top of the leg or at the toe, but desirably it is begun at the top of the leg and circular knitting proceeds in the ordinary manner to the commencement of the stripe 67. Thereupon the needles for the first reciprocation of 60 split work are divided into two groups, one group consisting of all the long butt or instep needles and all the short butt or heel needles excepting said thirty-six short butt 65 needles at the back of the ankle, and the

second group consisting of said thirty-six needles.

Assuming that the stocking is to commence at the top of the leg and the reinforced or contrasting area is to be a tapered high splice 70 of the general character hereinbefore described, the knitting proceeds in the usual manner for circular work, and the butts 61 of all the jacks 60 travel below the flanges 84, 85 of the two jack cams 86, 87, which cams 75 act upon the jacks during split work. Said cams 86, 87 are desirably fixed in position about the lower part of the needle cylinder, as indicated in Fig. 8. During circular work, the butts 61 of the jacks 60 merely pass idly 80 at their lowermost level below said flanges 84, 85 of the cams 86, 87. Preliminary to the commencement of split work, it is necessary to elevate all of the jacks 60, so that their needles, which are short butt needles, may be 85 brought into the upper level with the long butt needles, it being noted that preliminary to commencing reciprocating knitting all the long butt needles are elevated by the instep cam 27 to the upper level.

For the purpose of so elevating the jacks 60 I provide a cam 88 having two sloping faces 89, 90 meeting at a point, said cam being positioned in a space of suitable width between the cams 86, 87 and being movable into and out of operative position.

While any suitable means may be provided to move the said cam 88 into and out of position, I desirably employ the following means by which said cam is moved radially under 100 the control of a cam upon the pattern cam shaft 9. I will describe the said means without specifically limiting myself thereto.

As most clearly shown in Fig. 4, I provide a bracket 91 secured to the bed plate and beneath the same position for radial movement, the said cam 88, the latter being provided with a pin 92, extending up through a radial slot 93 in the bracket 91. A lever 94 pivoted at 95 has a forked end 96 engaging the pin 92, 110 whereby movement of said lever moves the cam 88 into or out of functioning position.

At its outer end the said lever 94 is connected at 97 to a link 98 which is connected to a lever arm 99 upon a shaft 100 mounted 115 in a suitable bracket 101 and having fast thereon a lever arm 102 which is connected at 103 to a long downwardly extending link 104 shown most clearly in Fig. 3. At its lower end the said link is connected at 105 to a lever pivoted at 106 and having two arms 107, 108, the latter terminating in a toe 109 adapted to ride upon a cam 110 on the cam shaft 9, or to enter the space 111. So long as the lever toe rides upon the cam 110, the jack cam 88 is held in its outermost or inactive position, but when said lever toe drops into the space 111, said cam 88 is immediately moved into its inner or functioning position between the two jack cams 86 and 87, 130

but is removed therefrom desirably substantially as soon as all said jacks are moved to the upper level, which result is effected upon two successive strokes of reciprocation of the 5 needle cylinder. Viewing Fig. 11 it will be evident that when the cam 88 is in functioning position and the jacks are moving toward the left in said figure, such of the jacks as have not passed the cam 88 ride up along the 10 inclined face 90 of said cam 88 and then along the upper side of the ledge 84 of the cam 86, thereby moving to the upper level and consequently elevating their needles to the upper level. Upon the next stroke of reciprocation—namely, the stroke in the opposite direction, the remaining jacks ride up along the inclined face 89 of the cam 88 onto the upper face of the ledge 85 of the cam 87, so that said remaining jacks move to the upper 15 level and thereby carry their needles to the upper level. At this stage in the operation, all the needles are at the upper level except those short butt needles which are without jacks and in the ensuing reciprocations 20 short butt needles are periodically brought down to the lower level, beginning at the inner ends of the two series of short butt needles, namely, those short butt needles which are in two groups at the sides of said 25 thirty-six or other selected number of short butt needles by which the stripe is made.

In split work as practised heretofore, prior to the invention disclosed in the said Lawson patent, the long butt needles knit at that side 30 of the machine having the single yarn guide 52, that is, at the auxiliary side and the short butt needles knit at the opposite side of the machine,—namely, that having the group 35 of yarn guides 41,—the regular side,—it being understood that the two short butt needles standing respectively at the two ends of the short butt series function as suture needles by acting with both sets of needles.

In the present organization this arrangement is continued so that the long butt needles knit at the side having the finger 52 the auxiliary side, and the other group of needles knit at the side having the yarn guides 41 the regular side. In the present organization, as in the disclosure in said Lawson patent, when a jack is at the upper level, the needle pertaining thereto knits with the long butt needles at the long butt or instep needle side—that is, at the auxiliary side. 45 In order to effect the automatic transfer of a needle from time to time from the larger group into the smaller, I employ jack picking means—this broadly being disclosed in the said Lawson patent, but as hereinbefore stated, and as hereinafter more fully described, I provide means for rendering said jack picking means inoperative from time to time, so as to produce the zigzag or like characteristic appearance of Fig. 9. This is 50 wholly new in the art and may be accom-

plished in different ways. I will describe the preferred embodiment of means for accomplishing the result stated without limiting my invention thereto.

I employ a single double-acting widening 70 jack picker, which acts in each direction of stroke of the needle cylinder, so as to pick down one after another the jacks from the inner ends of the two series of short butt needles which had previously been elevated to 75 the upper level by the cams 86, 87, 88.

One form of such widening jack picker is represented at 112 in the several figures. It is provided with two notches 113, 114 respectively, these notches as shown being each of 80 a size to bring down one jack at a time. If desired and within the scope of my invention either or both notches may be of a size to bring down two or a plurality of jacks at the same time, and if an irregular formation is 85 desired, one of the notches may be larger than the other so as to bring down more needles. Desirably, however, the two notches are of the same size.

The said picker 112 is pivoted within a 90 space 115 between ears 116, 117 of a post 118 as shown most clearly in Figs. 4 and 5, so that said picker may be rocked in a vertical plane against the force of a coiled spring 119 surrounding its pivot. The said post 118 itself 95 is provided with a vertical stud 120 shown most clearly in Fig. 5 as received in a suitable socket in the bracket 121 itself supported upon the ledge 4. The post 118 has capacity to turn in a horizontal plane and therefore 100 the picker 112 may move in either a horizontal or a vertical plane or in a resultant inclined plane. The said picker, when in its active upper position, is received in a central notch within a guard or levelling cam 123, as 105 shown most clearly in Fig. 7. Adjacent to the functioning end of the picker 112 is a plate 124 (Fig. 7) supported upon the bracket 121 and provided with a slot having the two inclined portions 125, 126, which at their 110 meeting point receive the functioning end of the picker 112. The said inclined portions 125, 126 act, upon depressions of the widening picker through engagement with a jack, to cause said picker to move in an inclined path 115 which is the resultant of the vertical and horizontal planes in which said picker and its post 118 are respectively mounted to move.

The said picker 112 is positioned as shown in Fig. 17 in the gap or space where the thirty-six or other selected number of centrally positioned short butt needles are without jacks 60.

In Fig. 16, I have indicated by the bracket 127 the long butt needles and by the bracket 128 all of the short butt needles. 125

I have not herein attempted to show the actual number, but preferably I provide about one hundred and twenty-eight long butt and one hundred and twenty-eight short butt needles in a three and a half inch diameter 130

cylinder and in such case I may omit the jacks for substantially thirty-six centrally located short butt needles, and provide jacks for the remaining short butt needles indicated by the two groups 129, 130 in Fig. 17. I have not attempted in said figure to indicate the actual number of needles, but in the example referred to there would be about forty-four needles in each of the groups 129, 130.

I provide two independent means to act upon said widening jack picker 112. One of these means is intended to hold said widening picker out of functioning position upon the commencement of each stroke of reciprocation, such inactive position continuing for a part only of the stroke and being for the purpose of preventing said picker 112 from acting upon the jacks of the needle groups 129, 130 which are nearest the long butt needles, but permitting said picker to act upon the jacks at the inner or adjacent ends of said groups 129, 130.

The other means provided to act upon the widening picker 112 is for the purpose of rendering said picker wholly inactive for the course or courses when the parts of the suture seams are made which do not cross the wales of the fabric, such, for example, as the parts 75 to 81 of Fig. 9.

I will describe the preferred embodiment of said two independent means to act upon the widening jack picker 112 without limiting myself to such means.

As shown in Figs. 2, 3, 4 and elsewhere, the so-called "104" gear is indicated at 131. It rotates once for every four revolutions of the needle cylinder, and therefore rotates one fourth revolution substantially once for each complete stroke of reciprocation of the needle cylinder. Meshing therewith is a smaller gear 132 which has one half the number of teeth of the gear 131 and therefore makes one half turn at each revolution or stroke of the needle cylinder. Said gear 132 is fast upon a horizontal shaft 133 mounted in suitable bearings extending upwardly from the bracket 134 upon the framing of the machine. Fast upon the opposite end of said shaft 133 is a drum 135 (see Figs. 4 and 6) which therefore makes one half revolution at each revolution or stroke of the needle cylinder. Upon said drum are two cams, one of which is indicated in part at 136, and is provided with opposite tapered ends, and the other of which is indicated at 138. The said drum 135 rotates in a direction toward the top of the sheet with regard to the portion of the surface of said drum visible in Fig. 4. Within the path of rotation of the cam 136 is a lever 139 pivoted at 140 and having a roll 141 adapted to be engaged by said cam 136 for a purpose to be hereinafter referred to.

As clearly shown in Fig. 4, the cam 136 takes under and rocks the arm 142 of a lever pivoted at 143 and having an arm 144 extend-

ing over and also beyond the jack picker 112 and beneath a lever arm 145. Therefore upon each stroke of reciprocation of the needle cylinder the jack picker 112 is moved downward for the commencement of such stroke and so that said picker cannot act upon the outermost jack of the group 129 or 130, as the case may be. The release of the lever 142, 144, from the cam 138 permits the picker 112 to be elevated partly through the influence of the coil spring 119 and partly if desired through a spring connected to the lever 142, 144, thus restoring said picker to its active position and in time to permit said picker to act upon the terminal jack at the inner end of the group 129, 130, as the case may be.

The lever 145 is pivoted at 146 upon the framing and at its outer end has a pin taking into a slot 147 in a link 148 extending downwardly as represented in Fig. 1. Its lower end is connected to the arm 149 of a pawl pivoted at 150 and having a pawl member or arm 151 adapted to engage the pattern chain moved by ratched 152 upon the pattern shaft 9. When the pawl arm 151 is down, the link 148 being moved vertically upward, rocks downwardly the arm of the lever 145 that engages the lever 144 and hence moves said lever 144 and the jack picker 112 downwardly into inoperative position. Thus the position of the pawl 149, 151 determines the periods of activity and inactivity for complete strokes of reciprocation of the widening jack picker 112.

The position of said pawl 149, 151 is determined by pattern means and preferably by lugs or formations upon the pattern chain 153. To that end said pattern chain may be provided with lugs of suitable length, as, for example, relatively short lugs 154 shown in Fig. 1a or longer lugs 155 shown in Fig. 1b, which extend in each instance to the adjoining shorter lugs 154, thus providing a double length or prolonged surface. Obviously the length of the lugs 154 or 155 may be varied as desired with the result that they take under and hold elevated for the desired length of time said pawl 149—151. Therefore depending upon the lugs 154, 155, the widening jack picker is held out of active or functioning relation and during such time the parts of the suture seams are formed which extend along wales of the fabric without crossing the same, as, for example, the parts 75 to 81 of Fig. 9.

I have stated that the cam 48 (Fig. 11) is moved out of active position for a part of each stroke of reciprocation so as not to interfere with the butts of the needles at the upper level. While any suitable means may be provided for the purpose, said cam is desirably operated by the cam 136 upon the drum 135 through the lever 139. For this purpose said lever 139 is provided with an arm 157, the

edge of which takes against a collar 158 upon a link 159 which at one end is pivotally connected at 160 to a link 161 (see Fig. 6) operatively connected in any suitable manner, not 5 shown to said cam 48 for moving the said cam as stated. The opposite end of said link 159 is connected to a lever 162 upon a shaft 163 mounted in the framing of the machine and having fast upon its end opposite the lever 162 10 an arm 164. To the outer end of said arm 164 at 165 is pivotally connected a link 166 which as shown most clearly in Fig. 1 extends downwardly to and is pivotally connected to a suitable lever 167 adapted to be operated by 15 a cam 168 upon the pattern drum 10.

I have in Fig. 10 indicated upon an enlarged scale a portion of one of the suture seams when formed as indicated in Fig. 9. It is unnecessary to describe the loop formation in detail, but it will be observed that at 20 the upper portion of said figure within the bracket 169 the suture seam extends parallel to the wales, at the portion within the bracket 170 said suture seam crosses wales of the fabric, and within the bracket 171 said suture seam again extends parallel with the wales of the fabric without crossing the same.

I have described in detail means whereby and desirably through the action of a widening jack picker, the tapered formation is provided in a series of steps which progressively enlarge the high splice area. My invention is not limited to the formation of a high splice area nor to the formation of a zone or area, 35 the size of which is always increased by steps, since within the scope of my invention I may provide means whereby a zone or area may first be enlarged by steps and then decreased in size by steps. Such a zone or area would 40 or might be roughly speaking of a diamond form but with zigzagged or stepped sides. To provide such an area I preferably employ a widening jack means such as that herein described and also provide a narrowing jack 45 means which may be rendered periodically active and inactive as may be required and in accordance with the dictates of the pattern chain or some suitable pattern formation. Without limiting myself thereto I will describe 50 one form of means for that purpose which is shown in Fig. 18.

In said figure wherein I have also shown the widening jack picker 112 and a portion of its 55 controlling means, I have represented a single double-acting narrowing jack picker 172 having two notches, one of which is shown at 173 and which notches may each control a single jack or either may control two or a plurality of jacks. The said narrowing jack picker is pivoted at 174 in a manner similar to the widening jack picker 112, so that it may 60 have a resultant movement in oblique lines. When said picker is down, it is in functioning 65 position, but when elevated, it is in inactive

position. To control the position of said narrowing jack picker 172 I have provided a lever 175 pivoted at 176 upon the framing and connected at its outer end at 177 with a link 178 extending downwardly to and pivotally connected to a lever 179 itself pivoted upon a stud 180 and having an arm 181 adapted to ride upon a cam or series of cams 182 upon a formation carried by the pattern cam shaft 9. When the lever 179 rides upon the cam 182 the narrowing jack picker 172 is out of action, but when said lever 179 rides in a space 183 said narrowing jack picker 172 is brought into action and therefore the suture seams will be caused to cross wales of the 70 fabric for a number of courses depending upon the length of the space 183. Any other suitable means may be provided to accomplish the broad result of decreasingly varying the number of short butt needles taking 75 yarn at the regular or primary side, thereby causing the suture lines to approach in a step by step manner instead of receding in a step by step manner as is the case when the widening jack picker 112 is functioning.

Having thus described one illustrative embodiment of the mechanism of my invention, the article thereof and the best mode known to me for practising my invention, I desire it to be understood that although specific terms 80 are employed, they are used in a generic and descriptive sense and not for purposes of limitation, the scope of the invention being 85 set forth in the following claims.

Claims:

1. In a circular knitting machine for the production of split work, a needle cylinder having a circular series of needles, a cam carrier having at least two spaced sets of stitch cams, means relatively to reciprocate said needle cylinder and cam carrier, means to introduce distinct yarns to needles at said stitch cams respectively, and cooperating means to cause substantially simultaneous knitting at both cam sets and the interengagement of the fabric sections knitted thereat, thereby forming split work with suture seams, and means whereby during the formation of split work a plurality of groups of successive courses are formed, in each of which groups inclined suture wales cross wales of the fabric but are formed upon a different series of needles than those of other of said groups, so that said inclinations progress as a whole transversely of the fabric, and a plurality of groups of interposed successive courses are formed during each of which the suture seams continue along wales without crossing the same but in parallelism with each other, said means including jacks for certain of said needles, each of said jacks being distinct from but adapted to move independently of its needle, and also subsequently with its needle to move the latter,

and a single, double-acting, jack picker to act upon said jacks.

2. In a circular knitting machine for the production of split work, a needle cylinder having a circular series of needles, a cam carrier having at least two spaced sets of stitch cams, means relatively to reciprocate said needle cylinder and cam carrier, means to introduce distinct yarns to needles at said 10 stitch cams respectively, and cooperating means to cause substantially simultaneous knitting at both cam sets and the interengagement of the fabric sections knitted thereat, thereby forming split work with suture seams, 15 jacks for certain of said needles, each of said jacks being distinct from but adapted to move independent of its needle and also subsequently with its needle to move the latter, and a single double acting jack picker to act upon said 20 jacks.

3. In a circular knitting machine for the production of split work, a needle cylinder having a circular series of needles, a cam carrier having at least two spaced sets of 25 stitch cams, means relatively to reciprocate said needle cylinder and cam carrier, means to introduce distinct yarns to needles at said stitch cams respectively, and cooperating means to cause substantially simultaneous 30 knitting at both cam sets and the interengagement of the fabric sections knitted thereat, thereby forming split work with suture seams, certain of said needles less than the entire number each having a jack distinct 35 from but adapted to move independent of its needle and also subsequently with its needle to move the latter, a single double acting, jack picker to act upon said jacks and means to render said jack picker inoperative at one or more times during split work.

4. In a circular knitting machine for the production of split work, a needle cylinder having a circular series of needles, a cam carrier having at least two spaced sets of 40 stitch cams, means relatively to reciprocate said needle cylinder and cam carrier, means to introduce distinct yarns to needles at said stitch cams respectively, and cooperating means to cause substantially simultaneous 45 knitting at both cam sets and the interengagement of the fabric sections knitted thereat, thereby forming split work with suture seams, certain at least of said needles each having a jack distinct from but adapted to move independent of its needle and also subsequently with its needle to move the latter, a single, double acting, jack picker to act 50 successively upon said jacks, pattern chain means, and means to control said jack picker from said pattern chain.

5. A circular knitting machine comprising in combination, a series of needles, a carrier therefor, a cam support, means relatively to rotate said carrier with its needles and said support to produce tubular work,

means relatively to reciprocate said carrier with its needles and said support thereby simultaneously to produce a plurality of segmental portions, and means to unite during the knitting operation said segmental portions by lines of suture loops, said means including a series of jacks and a corresponding series of needles, each of said jacks being distinct from but adapted to move independent of its needle and also subsequently with its needle to move the latter, and a single double acting jack picker to act upon said 70 jacks.

6. A circular knitting machine comprising in combination, a series of needles, a carrier therefor, a cam support, means relatively to rotate said carrier with its needles and said support to produce tubular work, means relatively to reciprocate said carrier with its needles and said support thereby simultaneously to produce a plurality of segmental portions, and means to unite during the knitting operation said segmental portions by lines of suture loops, said means including a series of jacks and a corresponding series 90 of needles, each of said jacks being distinct from but adapted to move independent of its needle and also subsequently with its needle to move the latter, said means including a single, double acting, jack picker to 95 act upon the jacks, and means to render the same inoperative at times during split work.

7. In a circular stocking knitting machine for the production of stockings having split work, a needle cylinder having a circular 100 series of needles, a cam carrier having two spaced sets of stitch cams, means relatively to reciprocate said needle cylinder and said cam carrier for the production of a split work area in said stocking, means to introduce distinct yarns to needles at said stitch cams respectively, cooperating means to cause substantially simultaneous knitting at both cam sets and the interengagement of the fabric sections knitted thereat, thereby producing 110 in the stocking split work with suture seams, certain of said needles less than the entire number each having a jack distinct from but adapted to move independent of its needle and also subsequently with its needle to move the latter, a single, double acting, jack picker and means to render said jack picker inoperative at one or more times during split work.

8. In a circular stocking knitting machine for the production of split work, a needle cylinder having a circular series of needles, a cam carrier having two spaced sets of stitch cams, means relatively to reciprocate said needle cylinder, and cam carrier to form the high splice or ankle portion of the stocking, means to introduce distinct yarns to needles at said stitch cams respectively, cooperating means to cause substantially simultaneous knitting at both cam sets and the 125 130

interengagement of the fabric sections knitted thereat, thereby forming the ankle portion, jacks for certain at least of the needles at the high splice portion and a single double acting jack picker to act upon said jacks.

9. In a circular stocking knitting machine for the production of split work, a needle cylinder having a circular series of needles, a cam carrier having two spaced sets of stitch cams, means relatively to reciprocate said needle cylinder, and cam carrier to form the high splice or ankle portion of the stocking, means to introduce distinct yarns to needles at said stitch cams respectively, cooperating means to cause substantially simultaneous knitting at both cam sets and the interengagement of the fabric sections knitted thereat, thereby forming the ankle portion, certain at least of the needles for forming the high splice portion having jacks, a single, double acting, jack picker for said jacks, and means to render said picker periodically inoperative during suture work.

10. In a circular knitting machine for the production of split work, a needle cylinder having a circular series of needles, a cam carrier having at least two spaced sets of stitch cams, means relatively to reciprocate said needle cylinder and cam carrier, means to introduce distinct yarns to needles at said stitch cams respectively, and cooperating means to cause substantially simultaneous knitting at both cam sets and the interengagement of the fabric sections knitted thereat, thereby forming split work with suture seams, said needles being in two groups, needles of one group only having jacks each of which is distinct from but adapted to move independent of its needle and also subsequently with its needle to move the latter, a single double-acting widening jack picker, and means to cause said picking means to act upon jacks in each course of two series of courses and for restraining said jack picking means from acting upon jacks during a course or courses between said two series of courses.

11. In a circular knitting machine for the production of split work, a needle cylinder having a circular series of needles, a cam carrier having at least two spaced sets of stitch cams, means relatively to reciprocate said needle cylinder and cam carrier, means to introduce distinct yarns to needles at said stitch cams respectively, and cooperating means to cause substantially simultaneous knitting at both cam sets and the interengagement of the fabric sections knitted thereat, thereby forming split work with suture seams, said needles being in two groups, needles of one group only having jacks, said jacks being each distinct from and adapted to be moved independent of its needle and also subsequent with its needle to move the latter, a single double-acting widening jack picker, and

means to cause said widening jack picking means to act upon a jack, and thereby participating in the transfer of a needle from the jackless group to the other group.

12. In a circular knitting machine for the production of split work, a needle cylinder having a circular series of needles, a cam carrier having at least two spaced sets of stitch cams, means relatively to reciprocate said needle cylinder and cam carrier, means to introduce distinct yarns to needles at said stitch cams respectively, and cooperating means to cause substantially simultaneous knitting at both cam sets and the interengagement of the fabric sections knitted thereat, thereby forming split work with suture seams, some at least of said needles having jacks each distinct from but adapted to move independently of its needle and also subsequently with its needle to move the latter, double acting jack widening picker means, and means to render the same inactive at the commencement of each stroke of reciprocation but permitting said picker means to become active before the termination of that stroke, so as to act upon the jack.

13. In a circular knitting machine for the production of split work, a needle cylinder having a circular series of needles, a cam carrier having at least two spaced sets of stitch cams, means relatively to reciprocate said needle cylinder and cam carrier, means to introduce distinct yarns to needles at said stitch cams respectively, and cooperating means to cause substantially simultaneous knitting at both cam sets and the interengagement of the fabric sections knitted thereat, thereby forming split work with suture seams, some at least of said needles having jacks each distinct from but adapted to move independent of its needle and also subsequently with its needle to move the latter, a widening jack picker, a cam drum, means to rotate the same twice for each relative reciprocation of the needle cylinder, said cam drum being operatively connected with said picker and having means to render said picker inactive for a part of each course in split work.

14. In a circular knitting machine for the production of split work, a needle cylinder having a circular series of needles, a cam carrier having at least two spaced sets of stitch cams, means relatively to reciprocate said needle cylinder and cam carrier, means to introduce distinct yarns to needles at said stitch cams respectively, and cooperating means to cause substantially simultaneous knitting at both cam sets and the interengagement of the fabric sections knitted thereat, thereby forming split work with suture seams, some at least of said needles having jacks each distinct from but adapted to move independent of its needles and also subsequently with its needle to move the latter, a

single, double acting, jack widening picker to act upon said jacks, and a plurality of distinct means for rendering the said picker inoperative.

5 In testimony whereof, I have signed my name to this specification.

FRANK E. JONES.
